W. M. KURZ,
INDICATOR AND ALARM FOR REFRIGERATOR DRIP PANS,
APPLICATION FILED NOV. 26, 1919.

1,384,767.

Patented July 19, 1921.

FIG. 2.

William M. Keay Inventor

UNITED STATES PATENT OFFICE.

WILLIAM M. KURZ, OF NEWARK, NEW JERSEY.

INDICATOR AND ALARM FOR REFRIGERATOR DRIP-PANS.

1,384,767.

Specification of Letters Patent. Patented July 19, 1921.

Application filed November 26, 1919. Serial No. 340,864.

To all whom it may concern:

Be it known that I, WILLIAM M. KURZ, a citizen of the United States, residing at Newark, in the county of Essex and State 5 of New Jersey, have invented certain new and useful Improvements in Indicators and Alarms for Refrigerator Drip-Pans, of which the following is a specification.

My invention relates to improvements in 10 an indicator and alarm for refrigerator drip pans and has for its primary object to provide a device for indicating the level of the liquid within the pan and an audible signal which is automatically sounded when the 15 liquid reaches a pre-determined height, so as to prevent the overflow of the pan.

A further object of the invention lies in 20 the provision of a device of the above mentioned character including a fulcrumed lever which automatically controls the operation 25 of the indicator and the sounding of the audible signal.

A further object of the invention lies in 30 the provision of a device of the above mentioned character including comparatively few and simple parts, which when assembled are reliable and efficient in operation, and inexpensive to manufacture.

Other objects and advantages of the invention will be apparent during the course 35 of the following description.

In the accompanying drawings forming a part of this specification and in which like numerals are employed to designate like 40 parts throughout the same,

Figure 1 is a side elevation of a refrigerator having my invention associated therewith, and

Fig. 2 is a diagrammatic view of the invention itself.

In the drawings, wherein for the purpose of illustration I have shown a preferred embodiment of my invention, the numeral 5 designates a refrigerator, of standard construction having disposed beneath the drain pipe 6, a drip pan 7 of any desired configuration.

As is usually the case, the refrigerator is 50 placed adjacent the wall of the room in which it is positioned and therefore, I have found it desirable to affix the principal parts of my invention to the wall directly in the rear of the refrigerator. As clearly shown 55 in Fig. 1, a bracket 8 is fixedly attached to the wall through the medium of bolts or screws 9 which pass through the upwardly

extending end 10 of the bracket. This bracket is located so as to be approximately on a horizontal plane with the under side of the refrigerator. The opposite end of the 60 bracket is bent downwardly at right angles, as at 11, having its lower edge rolled to form bearings 12. This downwardly extending portion is longitudinally slotted as at 13, to receive the lever 14 which is fulcrumed 65 thereto adjacent one end by the shaft 15. The lever 14 extends beneath the refrigerator and terminates in an arcuate shaped end 15' having depending therefrom a float 16 which is constructed of cork or other 70 suitable material. This float is connected to the end 15' through the medium of the lug 17 so as to hang within the pan 7. The opposite end of the lever 14 is apertured to receive the vertically extending rod 18 which 75 extends proportional distances on each side thereof. The lower end of the rod has a weight 19 attached thereto, the purpose of which is to balance the float. The upper portion of the rod 18 extends through the 80 elongated slot 20 of the bracket 8, being connected to one end of the pointer 21 which is pivoted to the block 22, as at 23. The block 22 is affixed to the wall at a distance slightly 85 above the top of the refrigerator so as to be easily seen by a person in front thereof. The opposite end of the pointer 21 is adapted to move over the arcuate shaped dial 24 carried by the plate 22, said dial having at 90 each end an outwardly extending lug 25 for limiting the movement of the pointer.

The audible signal comprises the bell 26 having extending therefrom wires 27 and 28, the wire 28 including a source of current 29 which when the circuit is complete 95 sounds the bell 26. The wire 28 is grounded on the lever 14, as at 30, while the wire 27 is connected to the terminal 31 attached to one end of the bracket 8. Extending from the terminal 31 downwardly is the switch 100 contact or arm 32 which intermittently contacts with the lever 14, thus completing the circuit. The parts of the invention are so arranged that when the level of the liquid in the drip pan is very low the circuit will 105 be broken and the pointer 21 will be disposed near the lower end of the dial 24. As the liquid in the pan rises the pointer 21 will move upwardly while at the same time the circuit of the signal will be closed and 110 the bell sounded.

It is to be understood that the form of

my invention herewith shown and described, is to be taken as a preferred example of the same, and that certain changes in the shape, size, and arrangement of parts may be resorted to without departing from the spirit of the invention or the scope of the subjoined claims.

Having thus fully described my invention, I claim:—

- 10 A signaling device for refrigerator drip pans comprising a bracket having its ends bent at right angles in opposite directions to each other, one of said ends being secured to an object adjacent the pan, a lever pivotally connected, adjacent one end, to the
- 15

other end of the bracket, a float at the extreme end of the lever, a vertical movable rod passing through the bracket and opposite end of the lever, a weight at the lower end of the rod to balance the float, and indicating means connected with the upper end of the rod, operable by movement of the float.

In testimony whereof, I have affixed my signature in the presence of two witnesses. 25

WILLIAM M. KURZ.

Witnesses:

WILLIAM J. BAILEY,
FRANK S. JOHNSON.
